(57) **CLAIM**

The ornamental design for a robot animal torso as shown and described.

DESCRIPTION

FIG. 1 is a front perspective view of a robot animal torso made in accordance with the subject design, with close-dashed lines indicating a glow effect.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front perspective view of the robot animal torso showing the environment.

FIG. 9 is a front perspective view of the robot animal torso.

FIG. 10 is a front view thereof.

FIG. 11 is a rear view thereof.

FIG. 12 is a right side view thereof.

FIG. 13 is a left side view thereof.

FIG. 14 is a top view thereof; and,

FIG. 15 is a bottom view thereof.

The short-dashed lines in FIGS. 1-7, indicating a glow effect, depict environment and form no part of the claimed design. The short-dashed lines in FIG. 8, indicating a robot animal, depict environment and form no part of the claimed design. The long-dashed lines in FIGS. 1-15 depict portions of the robot animal torso and form no part of the claimed design.
